CLAIM

The ornamental design for an uninterruptible power supply control and display module, as shown and described.

DESCRIPTION

FIG. 1 is a front and bottom, left perspective view of an uninterruptible power supply control and display module showing our new design, the right side elevation being a mirror image of the left side elevation;

FIG. 2 is a bottom plan view, shown at a reduced scale, of FIG. 1 and the alternate embodiment shown in FIGS. 6-8, showing the control and display module resting in the housing of the uninterruptible power supply;

FIG. 3 is a front elevation view thereof;

FIG. 4 is a bottom plan view thereof;

FIG. 5 is a top plan view thereof;

FIG. 6 is a front elevation view of an alternate embodiment of FIG. 1, it being understood that the undisclosed right and left side elevations are mirror images of those of the embodiment shown in FIGS. 1-5;

FIG. 7 is a bottom plan view of FIG. 6; and,

FIG. 8 is a top plan view of FIG. 6.

The broken line showing of an uninterruptible power supply housing in FIGS. 1-5 are for illustrative purposes only and form no part of the claimed design.

The rear of the uninterruptible power supply control and display module forms no part of the claimed design.
